UNITED STATES PATENT OFFICE.

JAMES M. TEAHEN, OF DETROIT, MICHIGAN.

PACKAGE.

1,272,145.

Specification of Letters Patent.

Patented July 9, 1918.

Application filed November 6, 1916. Serial No. 129,842.

To all whom it may concern:

Be it known that I, JAMES M. TEAHEN, a citizen of the United States of America, residing at Detroit, in the county of Wayne 5 and State of Michigan, have invented certain new and useful Improvements in Packages, of which the following is a specification, reference being had therein to the accompanying drawings.

10 The invention relates to crating or boxing of fragile articles for protection during shipment, and it is the object of the invention to obtain a simple construction of package for safely holding such articles. More 15 specifically it is the object of the invention to obtain a package adapted for holding both the body and cover of a flushing tank, as hereinafter set forth.

In the drawings:

20 Figure 1 is a cross-section through a package;

Fig. 2 is a longitudinal section therethrough.

The specific article for which my package 25 is designed is a composition flushing tank, which is of a somewhat fragile nature and comprises a body or tank portion A having a metallic outlet fitting B in the bottom thereof; also a cover C which is adapted to fit over 30 the top of the body. To securely pack these articles in a single case it is necessary to hold the same out of contact with each other, and as both articles are highly finished it is equally essential to hold them out of contact

35 with the walls of the crate or box. This is particularly difficult in the case of a cover which is of a dish-shaped form and is highly finished on both top and sides. I have solved the difficulty by forming on the un-

40 derside of the cover a plurality of depending lugs D, which are formed integral therewith and in which are embedded fastening devices E for securing the same within the crate. The fastening device employed is 45 preferably a nut embedded within the lug D, with which a screw E' may be engaged.

Thus by placing the cover upon the holding board F and passing the screws E' through the latter into engagement with the nuts E 50 the cover will be securely attached to said board and will bear thereon only on the lower edge of the flanged sides.

The container may be a rectangular box G of any suitable construction within which 55 the body A is first placed. The container is

of greater internal dimensions than the external dimensions of the body, so that the walls are out of contact, and by forming an aperture or recess H in the bottom of the container which engages the fitting B, the body may be held in a central position. The board F to which the cover C is secured is then placed within the container G to bear upon the top of the body A, a yieldable packing strip I being placed therebetween. 60 The cover J for the container is then placed in position, said cover having depending lugs or strips K which bear against the board F to hold the same in position. The cover J is secured by nailing or otherwise to 65 cleats L secured to the outer sides of the container, as shown in Fig. 2.

With the construction described, the articles may be quickly packed and unpacked, and while in the container are held in fixed 75 position with their finished outer faces out of contact with the walls of the container.

The tank A is preferably provided with a hanger M in the form of an angle bar, which 80 engages a recess in the upper edge of the rear wall of the tank. To more securely hold the tank in position a strip N is attached to the partition F and is arranged to engage the recess and fit within the angle-shaped hanger M. This strip therefore 85 assists in holding the tank from lateral movement and in clamping the same to the container bottom.

What I claim as my invention is:

1. A package, comprising an outer container, a fragile tank and its cover within said container, a separating partition between the tank and cover acting as a clamping means for the former, and means for attaching the cover to said partition to hold 90 the same from contact with the walls of the container.

2. A package, comprising a fragile, externally-finished tank and a cover therefor, a container for receiving the same having 100 means for engaging the bottom of the tank to hold the same from lateral movement, the walls of said container being spaced from the finished walls of the tank, a partition within said container for dividing the same 105 into separate compartments for the tank and cover and bearing upon the former to hold the same from displacement, and means for securing said cover to said partition engageable with the unfinished interior 110

of the former and holding the externally-finished surface out of contact with the walls of the container.

3. A package, comprising a fragile, externally-finished tank and a cover therefor, a container for receiving the same having its bottom apertured to engage a fitting on the bottom of the tank and holding the side walls of said tank from contact with the side walls of the container, a partition for dividing the container into two compartments respectively containing the tank and the cover, said partition having a bearing on the upper edge of the tank, a lug on the unfinished inner surface of said cover, and a detachable securing device for engaging said lug and securing the same to said partition, whereby the finished outer surface of said cover is held from contact with the walls of the container.

4. A package, comprising a fragile, externally-finished flushing tank and a cover therefor, said tank having an outlet fitting projecting from the bottom thereof, a container for said tank and cover having an apertured bottom for engaging said fitting to hold the finished walls of the tank from contact with the walls of the container, a partition for dividing the container into separate compartments for the tank and its cover, said partition bearing against the upper edge of the tank, securing means for said cover passing through said partition, and a plurality of lugs on the unfinished inner surface of said cover adapted for engagement with said securing means, whereby the finished surface of the cover is held from contact with the walls of the container.

5. A package, comprising a fragile, externally-finished flushing tank and a cover therefor, said tank being provided with an outlet fitting projecting from the bottom thereof and with a hanger on the rear wall thereof of angle section, a container for said tank and cover apertured to receive said fitting to hold the finished sides of the tank from the walls of the container, a partition for dividing said container into separate compartments for the tank and its cover, a strip on said partition engageable with said angle section hanger and clamping said tank to hold the upper end thereof from lateral displacement, and means for securing said cover to said partition engageable with the unfinished interior thereof; whereby the finished exterior is held from contact with the walls of the container.

6. A package, comprising a fragile externally-finished flushing tank and a cover therefor, said tank having an outlet fitting projecting from its bottom and an angle section hanger arranged in a recess in its rear wall at the upper edge thereof, a container for said tank and cover having an apertured

bottom for receiving said fitting to hold the finished walls of the tank from contact with the walls of the container, a partition for dividing said container into separate compartments for the tank and cover, a strip secured to said partition engaging said angle section hanger and the recess in the rear wall of said tank, and means for securing said cover to said partition with its finished outer surface out of contact with the outer walls of the container, said means comprising screws passing through the partition and engaging lugs on the inner face of the cover.

7. In a package, a container having separate compartments for a pair of articles, a partition for dividing the container into said separate compartments and serving to clamp one of the articles in position, and means for securing the other article to said partition, comprising securing devices passing through the partition and engaging lugs on said article.

8. In a package, a container having separate compartments for a tank and its cover, a partition for separating said compartments constituting a clamping means for said tank, and means for securing said cover to said partition comprising securing devices passing through the partition, and lugs on the interior of the cover for engaging said securing devices.

9. A package, comprising an outer container, a fragile tank and a cover within said container, a separating partition between the tank and cover acting as a clamping means for one of said articles within the container, and means for attaching the cover to said partition to hold the same from contact with the walls of the container.

10. A package, comprising a fragile, externally-finished tank and a cover therefor, a container for receiving the same having means for engaging the bottom of the tank to hold the same from lateral movement, the walls of said container being spaced from the finished walls of the tank, a partition within said container for dividing the same into separate compartments for the tank and the cover and bearing upon the former to hold the same from displacement, and means for securing said cover to a wall of the corresponding compartment, said means being engageable with the unfinished interior of the cover and holding the externally-finished surface thereof out of contact with the other walls of said compartment.

11. A package, comprising a fragile externally-finished tank and a cover therefor, a container for receiving the same having its bottom apertured to engage a fitting on the bottom of the tank and holding the side walls of said tank from contact with the side walls of the container, a partition for

dividing the container into two compartments respectively containing the tank and the cover, said partition having a bearing on the upper edge of the tank, a lug on the 5 unfinished inner surface of said cover, and a detachable securing device for engaging said lug and securing the same to one of the walls of the compartment receiving the cover, whereby the finished outer surface of 10 said cover is held from contact with the other walls of said compartment.

12. A package, comprising a fragile externally-finished flushing tank and a cover therefor, said tank having an outlet fitting 15 projecting from the bottom thereof, a container for said tank and cover having an apertured bottom for engaging said fitting to hold the finished walls of the tank from contact with the walls of the container, a 20 partition for dividing the container into separate compartments for the tank and its cover, said partition bearing against the upper edge of the tank, securing means for said cover passing through a wall of the 25 compartment receiving the same, and a plurality of lugs on the unfinished inner surface of said cover adapted for engagement with said securing means, whereby the finished surface of the cover is held from contact with the walls of the compartment receiving the same.

13. A package, comprising a fragile externally-finished flushing tank and a cover therefor, said tank being provided with an 35 outlet fitting projecting from the bottom thereof and with a hanger on the rear wall thereof of angle section, a container for said tank and cover apertured to receive said fitting to hold the finished sides of the tank 40 from the walls of the container, a partition for dividing said container into separate compartments for the tank and its cover, a strip on said partition engageable with said angle section hanger and clamping said 45 tank to hold the upper end thereof from lateral displacement, and means for securing said cover to a wall of the compartment receiving the same engageable with the un-

finished interior of the cover, whereby the finished exterior thereof is held from contact with the walls of said compartment. 50

14. A package, comprising a fragile externally-finished flushing tank and a cover therefor, said tank having an outlet fitting projecting from its bottom and an angle 55 section hanger arranged in a recess in its rear wall at the upper edge thereof, a container for said tank and cover having an apertured bottom for receiving said fitting to hold the finished walls of the tank from 60 contact with the walls of the container, a partition for dividing said container into separate compartments for the tank and cover, a strip secured to said partition engaging said angle section hanger and the 65 recess in the rear wall of said tank, and means for securing said cover to a wall of the compartment receiving the same with its finished outer surface out of contact with the other walls of said compartment, said 70 means comprising screws passing through said wall and engaging lugs on the inner face of the cover.

15. In a package, a container having separate compartments for a pair of articles, 75 a partition for dividing the container into said separate compartments and serving to clamp one of the articles in position, and means for securing the other article to said partition, comprising securing devices passing through a wall of the compartment receiving said other article and engaging lugs upon said article. 80

16. In a package, a container having separate compartments for a tank and its 85 cover, a partition for separating said compartments constituting a clamping means for said tank, and means for securing said cover to a wall of the compartment receiving the same, said means comprising securing devices passing through said wall, and 90 lugs on the interior of the cover for engaging said securing devices.

In testimony whereof I affix my signature.

JAMES M. TEAHEN.
